GEORGETTE H. K. MATTISON, OF AMBLER, PENNSYLVANIA.

WASHBASIN.

1,361,887.

Specification of Letters Patent. Patented Dec. 14, 1920.

Application filed June 7, 1919. Serial No. 302,383.

To all whom it may concern:

Be it known that I, GEORGETTE H. K. MATTISON, a citizen of the United States, residing at Ambler, in the county of Montgomery and State of Pennsylvania, have invented certain new and useful Improvements in Washbasins, whereof the following is a specification, reference being had to the accompanying drawings.

My invention relates to wash basins and the like, and, particularly, to a type of basin suitable for use in shampooing, or in otherwise washing or treating the head. It is my aim to provide a basin structure which shall afford the utmost possible comfort to the user,—i. e., the person whose head is being shampooed,—while at the same time affording the best possible protection against spilling or slopping over of the water or other fluid used and preventing the trickling of water down the neck of the user. Other advantages obtainable in connection with my invention will appear hereinafter, while its scope and essentials will be indicated in my claim.

The ordinary wash-basin commonly used for shampooing is subject to serious disadvantages, among which the following may be mentioned:

It does not allow the user to get sufficiently close to the bowl proper for his head to be completely over it;

It affords no security whatever against water finding its way down the neck and chest of the user;

It tends to keep the head of the user at too great a height above the water in the bowl, or else requires him to bend his head forward to an uncomfortably strained degree;

As a rule, the user is led to assume a strained and uncomfortable general posture in the endeavor to minimize these other disadvantages.

My new type of wash-basin not only overcomes the disadvantages just set forth and various others, but is also suitable and convenient for ordinary household use.

In the drawings, Figure I, is a plan view of a wash-basin structure embodying my invention.

Fig. II, is a corresponding front view in elevation.

In the embodiment here shown, my invention comprises a substantially horizontal

basin structure resembling, in general appearance, certain types now in ordinary household use. Its upper substantially flat surface around the bowl proper 1, is of ample width to hold such brushes, sponges, bottles, or other toilet articles as it may be desired to lay thereon, and also to afford space for suitable soap-dish depressions or bottle-holding sockets 2, 2, at its rear corners, and for the centrally located faucet-holes 3, 3, 3, behind the bowl. It is shown as having around its edges a relatively wide, deep depending "apron" 4. The corner portion 5, (between the apron and the top surface) overhangs horizontally and stands up beyond the adjacent surface vertically to about the extent usual in structures of this sort,—the upward extension going all the way around the structure and tending to prevent water from slopping or trickling over outside the structure. As shown, the basin structure is supported (on a massive pillar or pedestal 6) at about the ordinary height for such structures, so as to make it most convenient for an adult user when seated on a low stool; but it may be mounted at any other height if desired, and supported in any suitable manner. This particular structure is designed to present a generally "square" effect; but this is not essential to the purposes of my invention. The whole basin may be constructed in any desired manner and of any preferred materials, such as marble, porcelain, or porcelain-enamelled cast iron.

In order to permit the user to get his head well over the bowl 1, without discomfort, the front edge of the basin structure has, as shown, a vertical recess 10, relatively wide, and suitably curved to receive and conform closely to the natural outlines of the body (back or chest) of the average adult user when in an approximately upright or (forward or rearward) inclined position. In the top of this front edge portion of the structure, furthermore, is a corresponding horizontal recess or depression 11, relatively narrow as compared with the recess 10, and located about at its middle, so as to receive and conform closely to the neck, face, or head of the user when bent forward or backward to bring the head over the bowl. The curved surface of the depression 11 is of substantial extent or width as between the bowl 1 and the recess 10, so as

to afford an extended substantially flat and comfortable rest for the neck or head of the user.

These two substantially coincident or corresponding depressions 10 and 11, it will be seen, allow the user to get very close to the bowl 1, without discomfort, and to bring his face and forehead, or the back of his head, down to the very surface of the water 5 in the bowl without strain or constraint. The curved surfaces at 10 and 11, are not only more comfortable for the body and neck or forehead to rest against than are the surfaces of the ordinary wash-basin, 10 but fit the average user so closely (allowing for the elasticity of the flesh) as to prevent the trickling of water along the neck and body. They also tend to render more effective any towel or other means used for pur- 15 poses of protection against wetting.

Having thus described my invention, I claim:

A substantially horizontal wash basin-structure having in its front edge a relatively wide vertical recess adapted to receive the upright body of the user and a corresponding narrower horizontal depression, with curved surface of substantial extent from the bowl of the basin to said vertical recess, adapted to receive the user's neck or head and afford an extended flat, comfortable rest. 25 30

In witness whereof, I have hereunto signed my name at Newport, in the county of Newport and State of Rhode Island, this 35 second day of June, 1919.

GEORGETTE H. K. MATTISON.
